WIND MOTIVATED GARDEN DEVICE

Ralph C. Garrett, Huntington Park, Calif.

Application November 14, 1955, Serial No. 38,884

Term of patent 7 years

(Cl. D52—9)

FIG 1

FIG 2

Figure 1 is a view in perspective as viewed from the front of a wind motivated garden device embodying my new design; and

Figure 2 is a top plan view thereof.

I claim:

The ornamental design for a wind motivated garden device, substantially as shown.
